DISPENSER FOR NESTED PAPER
RECEPTACLES

Gerald C. Johnson, Bronxville, and Albert A. Perelman, Brooklyn, N. Y., assignors to Lily-Tulip Cup Corporation, New York, N. Y., a corporation of Delaware

Application April 9, 1948, Serial No. 19,956

8 Claims. (Cl. 312—43)

1

This invention relates to dispensing devices for nested paper receptacles; and the invention is especially useful in dispensing conical paper cups and receptacles such as sundae dishes. While suitable for other purposes and uses the invention is presently intended for use on counters, shelves, tables or the like in the dispensing of conical paper cups and dishes used in soda fountains, lunch counters, restaurants and the like places where drinks and foods are served.

It is customary in such places to utilize holders for this type of receptacle; the holders being provided with gripping means to engage and hold a single receptacle therein. Such gripping holder, in inverted position, is placed over the uppermost conical receptacle of a stack of inverted receptacles until it engages the receptacle which may then be withdrawn from the stack. The usual method of employing such gripping holders for individual cups is to place a stack of inverted receptacles on the counter, without any protecting casing; thus exposing the lips of the receptacles to dust and dirt with the attendant danger of spreading germs. Such a procedure also frequently results in withdrawing more than one receptacle from the stack unless prevented by the hands of the operator. Heretofore no satisfactory means has been found of covering the stack with the tip of the uppermost cup exposed at all times during the depletion from a full stack to a depleted stack. Such efforts as have been made entail cumbersome bulky devices which are not readily accommodated in the limited space usually available for counter or the like service.

An object of the invention is to provide a device of variable height for holding a stack of nested receptacles and adapted to automatically adjust its height in accordance with the height of said stack.

Another object is to provide a counter or the like dispenser for holding and encasing a stack of nested paper receptacles in inverted position and readily releasing individual receptacles therefrom as they are successively withdrawn from the upper end thereof, while retaining the remainder of the stack, wherein the height of the holder progressively decreases in conformity with depletion of the stack of receptacles.

Another object is to provide a device of the character described which may be readily adapted for use with receptacles of various sizes and having either rolled rim or plain lips.

The invention consists in the novel features of construction, arrangement, and combination

2

of parts embodied, by way of example, in the apparatus hereinafter described as illustrating a present preferred form of the invention, and the invention will be more particularly pointed out in the appended claims.

Further objects and advantages of the invention will more fully appear from the following description taken in connection with the accompanying drawings which show, by way of example, the present preferred embodiment of the invention.

Referring to the accompanying drawings in which the same reference characters indicate the same parts in the various views:

15 Fig. 1 is a perspective view of the device in its extended condition with a full stack of cups therein;

Fig. 2 is a similar view showing the device in its collapsed condition with a partly depleted stack of cups therein;

Fig. 3 is a top plan view of the device shown in Figs. 1 and 2 but with the cups removed;

Fig. 4 is a bottom plan view of said device;

20 Fig. 5 is a bottom plan view of a cap member of said device;

Fig. 6 is a perspective view showing further details of said device;

Fig. 7 is a somewhat enlarged sectional view taken along a vertical plane passing through the 25 diagonal 7—7 of Fig. 3, showing further details of the device in extended condition;

Fig. 8 is an exploded segmental perspective view showing stops for limiting axial and rotative movement of the casing sections relative to each other;

Fig. 9 is a view similar to Fig. 7 but showing the device in collapsed condition;

Fig. 10 is a fragmentary sectional view taken at line 10—10 of Fig. 9;

40 Fig. 11 is a similar view taken at line 11—11 of Fig. 9;

Fig. 12 is a similar view taken at line 12—12 of Fig. 9;

45 Figs. 13—16 are segmental sectional views illustrating respective cups of varying sizes to be used with rolled rim cups of correspondingly varying sizes;

Fig. 17 is a partial sectional view similar to Fig. 9 but showing the device adapted for and containing rimless receptacles, such as sundae dishes;

Fig. 18 is a bottom plan view of the cap member shown in Fig. 17; and

50 Fig. 19 is a bottom plan view of the adapter member shown in Fig. 17.

Referring to the drawings and more particularly to Fig. 1, it will be seen that the device comprises a base member 20, a plurality of hollow tubular sections 21, 22 and 23, telescopically disposed with respect to each other and relative to the base 20, and a cap 24 in the form of an annular ring. The full stack of cups is designated FS and the uppermost cup of the stack is designated C; the full stack maintaining the sections 21, 22 and 23 in extended position in the manner to be pointed out hereinafter. In Fig. 2 these sections are shown in fully collapsed condition, i. e., with the sections 23, 22 and 21 positioned within the confines of the base 20 and the cap or ring 24 lying closely adjacent the top of the base 20; in which condition the partially depleted stack is designated DS and the uppermost cup C thereof projects outwardly through the ring 24.

The base member 20 preferably is provided with a somewhat enlarged bottom of generally rectangular shape to provide for stability. To facilitate manufacture the base 20 (Figs. 3 and 4) is made in two parts, i. e., a body or shell 25 and a pedestal 26. The section 21 is freely slidably disposed within the shell 25 and is restrained against rotary motion relative thereto; the section 22 is similarly disposed and restrained with respect to the section 21 and the section 23 is similarly disposed and restrained with respect to the section 22, by means now to be described.

The body or shell 25 of base 20 is provided with an inwardly extending flange 27 whose internal diameter provides a freely sliding fit with the exterior diameter of the tubular section 21; and the flange 27 is (see also Figs. 2, 3 and 7) provided with a pair of diametrically oppositely disposed grooves or guideways 28 freely receiving a pair of ribs 29 projecting exteriorly of the section 21 and disposed on diametrically opposite sides thereof in parallelism with the axis. In a similar manner the section 21 is provided with an inwardly extending flange 30 whose internal diameter provides a freely sliding fit with the exterior diameter of tubular section 22; and the flange 30 is (Figs. 7 and 8) provided with a pair of corresponding guideways such as 31 freely receiving a pair of ribs 32 disposed in the manner above described relative to the ribs 29. Likewise section 22 and section 23 are respectively provided with a flange 33 having a pair of guideways such as 34 and with a cooperating pair of ribs 35 constructed and arranged in the manner above described relative to the respective pairs of telescoping members 20—21, 21—22 and 22—23. The guiding means just described serves the dual purpose of preventing angular movement of the four members relative to each other and of holding the parts in parallelism during their extension and retraction with respect to each other. Preferably the ribs 29, 32 and 35 are given a slight taper in width to provide a progressively decreasing width from bottom to top to facilitate the movement of the sections 21, 22 and 23 downwardly under the force of gravity.

The intermediate section 22 is provided (Figs. 7, 8 and 9) with an outwardly extending flange 36 of such diameter as to provide a freely sliding fit inside of the section 21 and to come into abutting engagement with the flange 30 of section 21 when the parts have been fully extended. Similarly, the section 23 has a similar outwardly extending flange 37 for cooperative association with the interior of section 22 and with flange 33

in the particulars just described. The several parts may be readily assembled by inserting the section 22 interiorly of the section 21 and the section 23 interiorly of the section 22 and then affixing the cap or ring 24, which is detachably secured to the top of section 23 by bayonet connections comprising (Figs. 5, 6 and 11) a pair of oppositely disposed lugs 38 carired on the section 23 and a pair of cooperating L-shaped grooves 39 provided in ring 24. The ring 24 is provided with a plurality of outwardly radially extending projections or lugs such as 40, preferably spaced equidistant to provide oppositely disposed pairs.

From the foregoing it will be seen that when the ring is in position the lugs 40 prevent the upper sections 23—22 from becoming disassembled. The lugs also provide a convenient means for grasping the ring for removal or assembly. The lower section 21 is next placed in the base member from the top, and it will be noted that it is free to be removed therefrom for the purposes to be later described.

Referring now to Figs. 9 and 4, it will be seen that the pedestal member 26 of the base is provided at its lower end with a bottom flange 41 which fits snugly within a seat provided in the lower end of the shell 25 and is secured in fixed position as by screws 42 (Fig. 12). The flange 41 is provided with recesses such as 43 disposed at its respective corners and friction plugs or discs such as 44 are secured therein to provide feet for the device. The top of the pedestal 26 is provided with a head 45 whose external surface is frustro-conical in shape, conforming to the interior shape of the cups to be dispensed and is centrally disposed within the hollow base member in such manner as to receive an inverted stack of cups.

The ring 24 (Figs. 3, 5 and 9) is provided with inwardly extending projections or fingers such as 46, preferably four in number and rounded on their inner ends. These fingers project inwardly of an internal peripheral flange 47 of said ring a distance less than the width of the beaded edge of the cup. The base of the flange 47 is adapted to fit a given size cup so as to hold several adjacent cups of the stack (Fig. 9) in register at this point while permitting free withdrawal of individual cups. The fingers 46 are so constructed and arranged as to support the ring 24 and one or all of the sections 23, 22 and 21 dependent from the rim of the uppermost cup of a stack, depending upon its height; while permitting ready withdrawal of one cup at a time.

It will thus be seen that the ring 24 serves the dual purpose of supporting the aforesaid members and providing a stripping means for individual of said cups which may be readily removed by being gripped interiorly of a holder in the manner well known in the art.

A full stack of cups may be inserted in the dispenser by lifting the ring 24 and assembled sections 23, 22 and 21 upwardly out of the base 20, placing a stack on the head 45 of pedestal 26, placing the sections 21, 22 and 23 over the stack, inserting the bottom of the lower section 21 in guided engagement within the hollow base member and the ring over the top of the stack until it comes into supported engagement with the rim of the uppermost cup (Fig. 7) at which time the dispenser is ready for use.

For cups of varying sizes having a rolled lip the ring 24 is removed and replaced by a ring having an internal diameter of corresponding dimen-

sions; otherwise no change is necessary and one dispenser, with a set of interchangeable rings, is adapted to handle cups of a number of different sizes. In Figs. 13-16 we have shown rings for respective cups of sizes 6 oz., 8 oz., 10 oz. and 12 oz.

The dispenser is also adapted to handle so-called sundae dishes or receptacles having a plain lip by the mere substitution of a suitable ring and an adapter for the pedestal head. Referring to Figs. 17-19, the base 20, casing sections 21, 22 and 23 and the pedestal 26 are identical with the device shown in Fig. 9. In this embodiment an adapter head 50 has been secured in position on top of the head 45 by an axial polygonal pin 51. The radial webs such as 53 serving to additionally center the adapter on the head 45. In place of the ring 24, as shown in Fig. 9, a ring 24d has been secured to the upper end of section 23 with the above described bayonet connections comprising the lugs such as 38 and L slots 39d provided in the ring 24d. The pin 51 is received in the corresponding hole 52 provided in the head 45. (see also Fig. 3) and the webs 53 (Fig. 17) are conformed to fit the tapered head 45 to hold the adapter firmly in alignment therewith. The top of the adapter is provided with a relatively widely flaring flange providing a frustro-conical head 54 conforming to the dish receptacles having a plain lip of the type illustrated as D, a few of which are disposed in stack formation to illustrate the relative position of the parts when the stack is nearly depleted. In this embodiment the ring 24d is provided with fin-like fingers such as 48d which are inclined on their lower faces to conform to the flare of the head 54 and the plain lip of a cup D and preferably have flat surfaces of limited extent which provide a support for the ring and dependent parts 23, 22 and 21 while permitting withdrawal of individual dishes from the upper end of the stack.

From the foregoing, and with particular reference to Figs. 7 and 8, it will be seen that with a full stack S disposed in the dispenser the casing sections 23, 22 and 21 will be suspended from the rimmed lip of the uppermost cup C with the lower end of section 21 disposed in the shell 27. As a cup C is withdrawn the sections move downwardly an increment equal to the thickness of one cup rim. During the first series of such movements the sections 23, 22 and 21 maintain their extended relation until the section 21 has telescoped to its lowermost position where it rests on the bottom 41 of the base. Upon further removal of cups section 22 continues to be suspended from section 23 and telescopes in section 21 until section 22 rests on the bottom 41; and upon further depletion of the stack section 23 continues to be suspended from the rim or lip of the uppermost cup of the stack until section 23 rests upon the bottom 41; the parts then being positioned as shown in Fig. 9, or Fig. 17 where rimless receptacles are being dispensed. It is noted that during this reduction of the height of the casing the sections move together in telescoping relation under the force of gravity and this is facilitated and insured by the parallel guideways and the limited frictional contact effected by means of the relatively narrow annular flanges 27, 30, 36, 33 and 37 (Figs. 7, 8 and 9). In the present embodiment the entire device (except for the screws and feet) is made of molded plastic. However, other embodiments have been made of different materials, and it is to be understood that in its several broader aspects the in-

vention is not to be limited to any particular material.

Having thus described our invention with particularity with reference to its presently preferred form, it will be obvious to those skilled in the art, after understanding our invention, that other changes and modifications may be made therein without departing from the spirit and scope of our invention, and we aim in the appended claims to cover such changes and modifications as are within the scope of the invention.

What we claim is:

1. In a dispenser for holding a vertical stack of inverted nested paper receptacles, the combination of a hollow base having a stack supporting portion centrally disposed therein for holding said stack axially thereof, a plurality of hollow tubular sections telescopically disposed with respect to each other and providing a variable-height casing for said stack, each of said sections being freely slidable axially relative to the respectively contiguous of said sections and the lowermost of said sections being disposed in said hollow base, and an annular member detachably secured in supporting engagement with the uppermost of said tubular sections provided with a throat slightly larger than the large diameter of the receptacles to be dispensed and having a plurality of peripherally spaced portions projecting inwardly of its interior diameter for spaced engagement with the lip of the uppermost receptacle of said stack for supported engagement therewith, said tubular sections being provided with cooperative portions supporting said successive lower sections from the respectively adjacent upper sections.

2. In a dispenser for holding a vertical stack of inverted nested paper receptacles, the combination of a hollow base member having a stack supporting portion centrally disposed therein for holding said stack axially thereof, a plurality of hollow tubular section members telescopically disposed with respect to each other and said base and providing therewith a variable-height casing for said stack, each adjacent pair of said members being provided with axially extending guide means comprising ribs disposed on respectively opposite sides of one of said pair of members slidable in cooperating guideways provided in the other of said pair of members, whereby each of said members is freely slidable axially and restrained against rotation relative to the respectively contiguous of said members, and an annular member detachably secured in supporting engagement with the uppermost of said tubular sections and provided with a plurality of peripherally spaced portions projecting inwardly of its interior diameter for engagement with the lip of the uppermost receptacle of said stack, said tubular sections being provided with cooperative portions supporting said successive lower sections from the respectively adjacent upper sections.

3. In a dispenser for holding a vertical stack of inverted nested paper receptacles, the combination of a hollow base having a stack supporting portion centrally disposed therein for holding said stack axially thereof, a plurality of hollow tubular section members telescopically disposed with respect to each other and providing a variable-height casing for said stack, each of said members being freely slidable axially relative to the respectively contiguous of said members, each adjacent pair of said members being provided with axially extending guide means comprising projections disposed on respectively opposite sides

of one of said pair slidable in cooperating guideways provided in the other of said pair and restraining individual of said members from rotation with respect to the others, and an annular member detachably secured to the top of the uppermost of said tubular sections, said annular member having projecting portions extending outwardly beyond its exterior diameter on respectively opposite sides to provide engageable means for removing said annular member from its supporting tubular section, said annular member being provided with a plurality of peripherally spaced portions projecting inwardly of its interior diameter for engagement with the lip of the uppermost receptacle of said stack, said tubular sections being provided with cooperative portions supporting said successive lower sections from the respectively adjacent upper sections whereby said annular member and pendant tubular members may be supported from the uppermost cup of said stack.

4. In a dispenser for holding a vertical stack of inverted nested paper receptacles, the combination of a hollow base, a stack supporting pedestal centrally disposed therein for holding said stack axially thereof, and a plurality of hollow tubular sections telescopically disposed with respect to each other and said base and providing therewith a variable-height casing for said stack, said sections having axially disposed guide means provided jointly thereby so constructed and arranged that each of said members is freely slidably axially and restrained against rotation relative to the respectively contiguous of said members, the uppermost of said tubular sections being provided adjacent its top with combined stripping and supporting portions projecting inwardly beyond the interior diameter thereof for engagement with the lip of the uppermost receptacle of said stack and said tubular sections being provided with cooperative portions supporting said successive lower sections from the respectively adjacent upper sections when said telescopic tubular sections are extended, whereby said tubular sections are adapted to be supported from the uppermost cup of said stack and provide a pendant stripping means.

5. In a dispenser for holding a vertical stack of inverted nested paper receptacles, the combination of a hollow base member having an open top and an open bottom, a stack supporting pedestal having a conically shaped head and a flanged lower end secured to the lower end of said base and centering said head axially of said open top, a plurality of hollow tubular section members telescopically disposed with respect to each other and said base and providing therewith a variable-height casing for said stack, each of said members being freely slidably axially in a downward direction relative to the respectively contiguous lower of said members, each of said upper tubular section members being restrained against axial movement upwardly beyond the top of its respectively contiguous lower tubular member and said lower section tubular member being movable upwardly beyond the top of said base, said members being provided with cooperatively engaging spline portions so constructed and arranged as to guide said members in parallel paths of movement, and an annular member detachably secured to the top of the uppermost of said tubular sections, and extending outwardly therefrom for abutting engagement with the top of the adjacent tubular section provided with a plurality of peripherally spaced portions project-

ing inwardly of its interior diameter for engagement with the lip of the uppermost receptacle of said stack.

6. In a dispenser for holding a vertical stack of inverted nested paper receptacles to be successively removed from the top thereof, the combination of a supporting head whose exterior conforms to the interior shape of said receptacles for receiving the lowermost receptacle of said stack and holding the same in vertical position, a variable-height casing providing a tubular enclosure for said stack and including a series of hollow casing sections in freely slidable telescopic relationship, the lowermost of said sections being held in vertical alignment and exteriorly concentric with said supporting head, the remaining upper of said sections being provided with limit stops disposed to come into abutting engagement when said remaining sections are fully extended one with respect to the other, and an annular member detachably secured to the top of the uppermost of said sections to provide for interchanging similar members adapted to cooperate with receptacles of different dimensions, said annular member being provided with inwardly extending peripherally spaced projections for engaging the lip of the uppermost receptacle of said stack, said projections being so constructed and arranged as to support said annular member and dependent sections from said uppermost cup lip while permitting disengagement of said lip and withdrawal of said cup upwardly from said stack, whereby upon diminution of said stack said telescopic sections correspondingly telescope under the action of gravity and the height of said casing decreases in conformity with the stack height.

7. In a dispenser for holding a vertical stack of inverted nested paper receptacles to be successively removed from the top thereof, the combination of a supporting head whose exterior conforms to the interior shape of said receptacles for receiving the lowermost receptacle of said stack and holding the same in vertical position, a variable-height casing providing a tubular enclosure for said stack and including upper, lower and intermediate hollow casing sections in freely slidable telescopic relationship, the lower of said sections being held in vertical alignment and exteriorly concentric with said supporting head, said intermediate section having an inwardly extending peripheral flange at its top and an outwardly extending peripheral flange at its bottom, said upper section having an outwardly extending peripheral flange at its bottom for cooperative abutting engagement with the upper flange of said intermediate section, said lower section having an inwardly extending peripheral flange at its top for cooperative abutting engagement with the bottom flange of said intermediate section, and an annular cap disposed over and detachably secured to the top of the upper of said sections to provide for interchanging similar members adapted to cooperate with receptacles of different dimensions, said annular member being provided with inwardly extending peripherally spaced projections for engaging the lip of the uppermost receptacle of said stack, said projections being so constructed and arranged as to support said annular member and dependent sections from said upper cup lip while permitting disengagement of said lip and withdrawal of said cup upwardly from said stack, whereby upon diminution of said stack said telescopic sections correspondingly telescope under

the action of gravity and the height of said casing decreases in conformity with the stack height.

8. In a dispenser for holding a vertical stack of inverted nested paper receptacles to be successively removed from the top thereof, the combination of a supporting head whose exterior conforms to the interior shape of said receptacles for receiving the lowermost receptacle of said stack and holding the same in vertical position, a variable-height casing providing a tubular enclosure for said stack and including a series of hollow casing sections in freely slideable telescopic relationship, the lowermost of said sections being held in vertical alignment and exteriorly concentric with said supporting head, the remaining upper of said sections being provided with limit stops disposed to come into abutting engagement when said remaining sections are fully extended one with respect to the other, and a separate annular member adapted for interfitting engagement with and secured to the top of the upper-

most of said sections whereby the same size tubular sections may be utilized with one or the other selected annular member in accordance with a predetermined size of receptacle to be dispensed, said annular member being provided with inwardly extending peripherally spaced projections for engaging the lip of the uppermost receptacle of said stack, said projections being so constructed and arranged as to support said annular member and dependent sections from said uppermost cup lip while permitting disengagement of said lip and withdrawal of said cup upwardly from said stack, whereby upon diminution of said stack said telescopic sections correspondingly telescope under the action of gravity and the height of said casing decreases in conformity with the stack height.

GERALD C. JOHNSON.
